(57) **CLAIM**

We claim the ornamental design for an automated teller machine, as shown and described.

DESCRIPTION

FIG. 1 is a front elevation of an automated teller machine showing our new design.

FIG. 2 is a top left perspective view thereof; and,

FIG. 3 is a top right perspective view thereof.

The broken lines in the drawings are for illustration only and form no part of the claimed design. The broken line showing of each a rectangular portion above the display a keypad, a circular element and the housing illustrate environmental elements and form no part of the claimed design.

1 Claim, 3 Drawing Sheets

FIG. 1
